(57) **CLAIM**

The ornamental design for a side cookware handle, as shown and described.

DESCRIPTION

FIG. 1 is a perspective view of the “side cookware handle” from above showing my new design;

FIG. 2 is a top plan view thereof;

FIG. 3 is a front elevation thereof;

FIG. 4 is a side elevation view thereof;

FIG. 5 is a bottom plan view thereof;

FIG. 6 is back elevation view thereof; and,

FIG. 7 is a perspective view thereof from below.

The pair of circular rivet holes shown in broken lines in the flange portion of the handle, which are visible at least partially in FIGS. 1, 3, 4 and 6-7, are functional elements and are not intended to be limiting the scope of the ornamental design. The broken lines represent portions of the design that form no part of the claim.
